POULTRY BLINDER CLIP

Milton Horowitz, Farmingdale, N. J., assignor to
 Harwood Company, Farmingdale, N. J., a firm
 composed of Milton Gene Harwood and Louis
 Jay Harwood

Application January 5, 1945, Serial No. 571,461

3 Claims. (Cl. 119—97)

1

My invention relates to blinders, and more particularly to anti-picking devices, which can be instantly attached to and removed from poultry.

The use of blinders on poultry for preventing cannibalism is conventional. The task of attaching and removing the blinders is burdensome, more especially when respiratory diseases attack a flock, and to facilitate breathing, it may become necessary to remove thousands of blinders in a relatively short time, from the beaks of poultry to which they are attached.

The principal object of my invention is to provide a spring locking type of blinder clip which may be easily applied to the nostrils of a chicken and readily removed therefrom.

Further objects are to provide a blinder of the foregoing type which may be opened by compressing the blinders and locked by releasing the pressure therefrom; to provide a blinder which may be readily inserted through the nostrils of a chicken's beak, and which will hold itself in position by spring pressure; and to provide a blinder provided with a piercing means, which is releasably engaged by a spring-actuated means normally locking the piercing means in position, and to provide blinders, including the spring actuated means, and the piercing device which are made of the same material, so that they may be moulded together as a unit, or stamped from a single piece of sheet metal, having springy qualities; to provide a blinder which may be applied to the beak of poultry, and removed therefrom by the use of one hand; to provide a blinder employing two piercing elements, one for each nostril of poultry; to provide a spring flexed blinder wherein the blinders are dihedrally positioned in the direction of flexure to facilitate a one hand flexing operation.

I accomplish these and other objects and obtain my new results as will be apparent from the device described in the following specification, particularly pointed out in the claims, and illustrated in the accompanying drawing in which:

Fig. 1 is a perspective view of my blinders in normal position.

Fig. 2 is a similar view with the spring compressed.

Fig. 3 is a view showing the blinders attached to a chicken's beak.

Fig. 4 is a top plan view illustrating the dihedral angle which the blinder may form to facilitate flexing the bowed portion.

In the drawing, Fig. 1, I have illustrated one form of my invention. It consists of a section having end portions 10 and 11, one for each eye,

2

made integral with a band 12 of springy material, such as spring steel, and a piercing device comprising elements 13 and 14. The spring normally supports the piercing elements in the position shown in Fig. 1, wherein the piercing elements are nearest to each other.

By applying the fingers 39 of one hand to the blinders, as shown in Fig. 2, and forcing the blinders towards each other, the spring 12 is flexed, and the piercing elements are pulled away from each other to the open position. The blinders may be given a slight dihedral angle, similar to that shown in Fig. 2 and Fig. 4, to facilitate the flexing of the spring in the right direction at the start of the flexing movement. Such a slight dihedral will not effect the normal blinder function.

In the position shown in Fig. 2, the blinders may be attached to the nostrils 15 of a chicken's beak 16. The pressure applied by the fingers 39 is progressively released until the piercing elements penetrate the apertures on each side of the chicken's beak, whereupon the fingers are removed and the spring forces the piercing elements toward each other to lock the blinders thereto, as shown in Fig. 3. The band 12 will rest on the beak 16 and support the blinders in proper position before the eyes 17 of the chicken, which permits inspection of the ground, but prevents forward sight.

It should be noted that the piercing elements in all cases should be as thin as possible so as not to obstruct normal breathing.

By the foregoing, I have accomplished the objects of my invention. I have provided a blinder for attachment to the beaks of poultry, that is spring locked into position, and which may be instantly released therefrom. The blinder may be entirely made of plastic having sufficient resiliency in the band position to spring lock the device. The piercing element may be in two sections as shown in Fig. 1. Further, the device may be stamped from a single piece of sheet metal, provided with sufficient springiness in the band portion, and shaped into the position indicated in Fig. 1.

By designing the parts as shown in Fig. 1, the device may be quickly and conveniently installed and removed from the beak of poultry with the use of one hand.

In the claims, the expression "spring acting locking means" is intended to cover any means which will secure the piercing means in position on the nostrils of poultry without loosening therefrom.

55

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. A blinder for poultry comprising spaced outer vision obstruction portions and an intermediate bowed connecting portion, the vision obstruction portion having pointed extensions adjacent the ends of the connecting portion and in

the space between the vision obstruction portions.

2. A blinder as defined in claim 1, wherein the spaced outer vision obstruction portions, the pointed extensions and the connecting portion comprise a structure made of a unitary piece of material.

3. The blinder of claim 1, wherein the vision obstruction portions and pointed extensions are formed at a dihedral angle to facilitate flexing towards each other to separate the pointed extensions.

MILTON HOROWITZ.
